LOCOMOTIVE STOKER

Menahem Rivkin, Philadelphia, Pa.

Application July 29, 1933, Serial No. 682,846

5 Claims. (CL. 110—101)

This invention relates to new and useful improvements in locomotive fuel stokers and is particularly adaptable for use in instances where the coal has not been previously screened before being placed in the locomotive tender and therefore contains a large percentage of very fine particles of coal.

The principal object of the invention is to provide a stoker for the purpose set forth arranged to effect the complete combustion or consumption of a maximum percentage of fuel within the locomotive fire box.

Another object of the invention is to provide a stoker assembly as set forth including means for screening the coal in the tender before delivery to the fire box for distribution on the grate, and segregating the fine particles from the more coarse pieces of coal in separate chambers for delivery to the fire box.

Another important object of the invention is to provide a stoker device having means for delivering the segregated coarse and fine coal separately and independently to the fire box of the locomotive for consumption.

A more specific object of the invention is to provide a stoker device having means for delivering the separated fine coal particles to the front end of the fire box for distribution over the grate thereof independently of the delivery of the more coarse coal in the customary manner to the rear of the fire box for distribution.

Another object of the invention is to provide a stoker device including means operable to vary the size and quantity of the fine coal separated from the more coarse coal, said means being operatively controlled at will from a point within easy access of the operator.

Another object of the invention is to provide a stoker device of the character set forth having means for independently controlling the distribution of the fine and more coarse coal, in respectively opposite directions from the front and rear of the fire box to effect more even distribution on the grate.

Another object of the invention is to provide a stoker device as set forth wherein the fine separated coal particles are delivered to the front end of the fire box for distribution in an opposite direction below the point of delivery of the more coarse coal at the rear of the fire box.

A still further object of the present invention is to provide a stoker device as set forth having means operable to effect operation thereof in the heretofore customary manner without screening the coal or where previously screened coal is used,

and as a double acting locomotive stoker when the coal is screened to deliver the fine screened particles separately to the fire box, said means being operable at will and suitably controlled from the locomotive cab.

These and other objects and certain features and details of invention are set forth hereinafter and disclosed in the accompanying drawings, in which:

Fig. 1a is one part of a fragmentary view in section longitudinally through the fire box of a locomotive.

Fig. 1b is the other part of the disclosure in Fig. 1a longitudinally through the tender of the locomotive.

Fig. 2 is a fragmentary view in section of a modification of the connection for delivering the fine coal adjacent the forward end of the fire box for distribution;

Fig. 3 is a view on line 3—3, Fig. 1b;

Fig. 4 is a view in section on line 4—4, Fig. 1a;

Fig. 5 is a fragmentary view similar to the disclosure in Fig. 4, showing a modified form of construction of the fire box grate and the stoker casing;

Fig. 6 is a view in section on line 6—6, Fig. 1b;

Fig. 7 is a view similar to Fig. 6, showing a modification of the stoker arrangement;

Fig. 8 is a fragmentary view in section showing a modified structure for delivering the coal to the forward end of the fire box;

Figs. 9, 10 and 11 show in detail the construction of the discharge fan embodied in the disclosure in Fig. 8; and

Figs. 12 and 13 are views showing still another modified form of construction for delivering the fuel to the forward end of the fire box.

Heretofore in the majority of instances, coal or like fuel has been fed to locomotive fire boxes by various means for distribution without being screened, which results in relatively large fuel losses. It is well known that coal of the type used for steam locomotive combustion contains a very large percentage of very fine particles of the fuel, which heretofore have been carried through the fire box and out of the smoke stack in an unconsumed state, since due to their extremely light weight and the high velocity of the draft and combustion gases passing upwardly through the fire box and over the fire brick arch, they do not fall to the fire bed or remain in the fire box long enough for complete or even partial combustion, and the strong draft carries them partly unburned through the fire tubes and out

of the smoke stack, resulting in unbelievable fuel or coal losses.

The present invention contemplates the provision in association with a locomotive tender, of means to permit screening of the coal and the segregation thereof from the more coarse fuel in a separate chamber, together with novel stoker means including the customary means for delivering the more coarse fuel to the rear of the fire box for distribution, and novel means for independently delivering the separated fine particles of fuel to the front end of the fire box for distribution. By distributing the fine coal independently of the coarse fuel rearwardly from the front end of the fire box in the same direction that the draft and gases are traveling, and at a point where the draft is of least velocity and more removed from the fire tubes, the fine particles of fuel are given a chance to drop onto the grate or fire bed while the very fine particles of coal kept in suspension have their traveling distance increased, to afford more time for combustion or consumption thereof within the fire box proper.

The distribution of the fine coal from the forward end of the fire box eliminates the usual inefficient practice of wetting coal before delivery and distribution over the grate, which results in a substantial reduction of the fire box temperature, consumes fuel for the evaporation of the moisture in the coal and fills the fire box with steam vapor, and prevents proper draft through and reduces the vacuum in the fire box. The delivery and distribution of wet coal on the grate puts an unnecessary burden on the stoker and its engine, which is especially severe in cold weather and occasionally is put entirely out of commission in instances when the wet coal freezes.

Referring now more particularly to the drawings and particularly to Figs. 1a and 1b thereof, A designates the customary fire box of a steam locomotive and B designates the tender or fuel hopper having a deck 1 provided with an opening 1a therein. A trough 2 provided with upper and lower chambers 3 and 4 respectively is secured to the underside of the hopper deck 1 of the tender, and the upper chamber 3 thereof is provided with downwardly converging wall or baffle members 5—5, spaced apart at their lower edges to afford passage from said upper chamber 3 to the lower chamber 4. A screen or sieve member designated generally as 6 is slidably mounted between the upper and lower chambers 3 and 4 of the trough 2 and arranged for horizontal movement with respect thereto. In the present instance the screen or sieve 6 is provided with a solid central portion 7 and screen or sieve portions 8 and 9 of relatively fine and coarser mesh, respectively, at either side thereof. Accordingly it will be seen that by movement of the sieve 6 laterally with respect to Fig. 6 of the drawings, the communication between the upper chamber and the lower chamber 4 may be entirely cut off by positioning the solid central portion 7 of the screen between said chambers or passage from the upper to the lower chambers may be had by positioning the finer or relatively coarser mesh screens 8 and 9, respectively therebetween depending upon the degree of fineness of the fuel it is desired to have pass into the lower chamber. The sieve 6 may be operated in any suitable manner such as by a rack and pinion 10 arranged to be operated at will from within the locomotive cab.

A conveyor screw 11 is mounted longitudinally within the chamber 3 of the trough 2 immediately above the opening at the bottom thereof and this conveyor screw 11 is connected by means of a universal joint 12 to a second conveyor screw 5 section 13 rotatably mounted within a casing 14 connected at its rearward extremity to the trough 2 by means of a joint 15 similar to a ball and socket arrangement, the forward end thereof being connected by means of a neck 16 to the 10 rear end 17 of the locomotive fire box A. A similar conveyor screw 18, which may or may not be of smaller diameter than the screw 11, is mounted longitudinally within the lower trough chamber 4, adjacent the bottom thereof and this conveyor screw 18 is connected through a universal joint 19 to another conveyor screw section 20, which is in turn connected through a universal joint 21 to another screw section 22, said conveyor screws 20 and 22 being rotatably mounted 20 within housings or casings 23 and 24, respectively, connected to each other and to the chamber 4 of the trough 2 by means of joints 25 and 26 similar to ball and socket arrangements, respectively. The forward end of the screw conveyor 22 is journaled in a neck 27 which connects the forward end of the conveyor casing 24 with the forward end 28 of the fire box.

The lower fuel stoker is shown in each instance as arranged to deliver fuel at the front end 28 30 of the locomotive fire box A below the fire arch F, and while this particular arrangement is preferable and affords a maximum fuel combustion with least fuel stack losses, it is pointed out that the delivery of the fine particles of coal 35 which have been separated from the more coarse thereof, may occur at any point longitudinally of the fire box between the front and rear walls thereof with increasing efficiency, depending upon the point of delivery with respect to the 40 forward end 28. It should be borne in mind, however, that such delivery of the fine coal in the fire box A should occur at a point below the point of delivery of the more coarse fuel at the rear end 11 of the fire box.

The conveyor housings or casings in the present instance are supported from the underside of the fire box at each end thereof by suitable supports 29 and 30 and a support 31 midway between the ends of said fire box is connected to 50 the underside of the central grate support 32. A shield 33 is positioned over the conveyor casings below the grate to deflect ashes and heat from the fire bed on the grate out of the path of said casings.

In the present instance the screw conveyor 11 is driven in the usual manner by means of a stoker engine (not shown) through a gear 34 on the conveyor shaft, and the lower conveyor screw 18 and its connected sections 20 and 22 60 are driven from the same stoker engine operating to drive the conveyor 11 through said gear 34 by means of a pivotally mounted gear 35 meshed with the gear 34 and movable into and out of mesh with a gear 36 fixed on the rear end of 65 the lower conveyor screw shaft 18. It will be seen therefore that by moving the gear 35 into or out of engagement with the gear 36, the lower stoker conveyor 18 may be placed in operation or not as may be desired under the particular 70 operating circumstances.

The apparatus controlling operation of the conveyor screws 11 and 18 is preferably arranged within the locomotive cab as has been customary in the past, but for the purposes of description 73

of this invention a lever 35a has been provided in the interests of simplicity to illustrate the manner in which the operation of the conveyors 11 and 18 may be respectively controlled.

5 The openings to permit entrance of fuel inwardly of the fire box A at each end 17 and 28, respectively, thereof are provided with the usual fuel distributing plates 37 and 38, together with the customary steam impelling nozzles or jets, such as at 39, 40 and 41.

10 In operation of the stoker, the fuel drops from the tender or hopper B into the upper chamber 3 of the trough in which is located the conveyor screw 11. Rotation of the conveyor screw 11 acts to shift and joggle fuel in the chamber and facilitates separation of the fine particles of fuel from the more coarse thereof, and accelerates 15 passage of said fine particles through the screen 8 or 9, whence they drop into the lower chamber 4 and are delivered to the front end of the fire box by the screw 18. To facilitate better screening 20 operation the upper conveyor screw 11 may be constructed with teeth or projections 11a on its threads to give the coal a circular motion and vibrate or jar the screen.

25 The fuel carried by the conveyors 11 and 18 is delivered to the discharge boxes or necks 16 and 27, from which it passes onto the distributing tables or plates 37 and 38. At the front end 30 the fuel is assisted by a jet 41 and from these tables the fuel is distributed over the fire box grate by means of jets 39 and 40. It will be noticed that the distributing plate 37 at the front end of the fire box is located at a point below the distributing plate 38 at the rear end 35 thereof, and disposed at such an angle of distribution that the fine coal is carried down on the grate not only by its own gravity but also by the dragging action and weight of the larger pieces of coal distributed from the higher level.

40 A modification of the lower conveyor casing below the fire box A is shown in Fig. 5 of the drawings, wherein the central grate support 32a and said casing are cast as an integral member with a vertical connecting web 42 having transverse strengthening webs 43.

45 A modification of the construction of the trough located beneath the fuel hopper B is shown in Fig. 7 and may be provided with a stationary screen 8a of predetermined fixed mesh. The bottom of the upper chamber 4a of this modified trough 2a is of semi-circular configuration to facilitate removal or replacement of the screen 8a with a solid partition or screens of different sized mesh. In this modified form the 50 sieve may also be composed of a number of sections having different sized openings, said sieve being arranged to move longitudinally of the conveyor screws 11 and 18 in order to bring the different sections or a blank section opposite the 55 opening in the trough 2a.

60 In addition numerous modifications may be incorporated in the construction of the discharge box or neck 27 for delivering the fine fuel from the lower conveyor screw 18 to the fire box. For instance, in Fig. 8 a distributing fan 44 is rotatably mounted within the discharge box or neck 27a and is driven by the screw shaft 22 through gears 45 and 46, rotatably mounted within a small housing 47 at the forward end of said discharge 65 box 27a. The fan 44 is formed with a number of radial diverging obliquely disposed buckets or pocket members 48, which when positioned within the discharge box 27a, pick up the fuel from the lower end of said discharge box at the for-

ward extremity of the conveyor screw and discharge the same inwardly of the forward end 28 of the fire box against a hood 49, which deflects the fuel into the path of a jet 40a and distributes said fuel from the distributing table or plate 37 over the fire box grate. In another form the fan 44 may be constructed as shown in Figs. 10 and 11, where the particular construction of the locomotive is more readily adaptable to a rectangular discharge box in contrast to the angular one 10 disclosed in Fig. 8, such as where the forward wall of the fire box is vertical and not forwardly inclined as in said Fig. 8. In addition the fuel may be carried from the end of the conveyor 22 through the discharge box 27b to the forward 15 end 28 of the fire box by means of a vertically positioned screw section 50 driven from the conveyor screw shaft by means of gears 51, 52 and the worm arrangement 53, 53a as shown in Figs. 12 and 13 of the drawings. 20

25 The present invention affords an ideal solution to the ever present problem of eliminating the comparatively large fuel losses in locomotive operation, and while a particular form of the invention has been set forth for the purpose of description, it is not intended that the same be limited precisely thereto within the scope of the annexed claims.

What is claimed is:

1. A steam locomotive having a fire box and a 30 fire arch extending inwardly of said fire box from one end wall thereof, a fuel hopper, a trough including upper and lower chambers disposed below said hopper and arranged to receive fuel therefrom, means for separating said chambers adjustably operable and constructed to permit fuel of predetermined fineness to pass to the lower chamber, means mounted in the upper chamber operable to deliver the more coarse particles of fuel therein to the other end of the fire box from 35 said fire arch, and means in the lower chamber operable to deliver the finer particles of fuel therein into the other end of the fire box at a point below and in a direction opposite to the feed of the more coarse particles of fuel. 40

45 2. A steam locomotive having a fire box and a fire arch extending inwardly of said fire box from one end wall thereof, a fuel hopper, a trough including upper and lower chambers disposed below said hopper and arranged to receive fuel therefrom, means for separating said chambers adjustably operable and constructed to permit fuel of predetermined fineness to pass to the lower chamber, means mounted in the upper chamber operable to deliver the more coarse particles of fuel therein to the other end of the fire box from 50 said fire arch, and means in the lower chamber operable to deliver the finer particles of fuel therein into the fire box adjacent the other end thereof at a point affording maximum 55 distance of travel for said fine particles of fuel through said fire box.

60 3. A steam locomotive having a fire box and a fire arch extending inwardly of said fire box from one end wall thereof, a fuel hopper, means associated with said hopper adjustably operable and constructed to segregate particles of fuel of predetermined fineness from the more coarse particles thereof, means operable to deliver the more coarse particles of fuel to the other end of the 65 fire box from said fire arch, and means operable to deliver the finer particles of fuel into the other end of the fire box at a point below and in a direction opposite to the feed of the more coarse particles of fuel. 70

4. A steam locomotive having a fire box and a fire arch extending inwardly of said fire box from one end wall thereof, a fuel hopper, means associated with said hopper adjustably operable and constructed to segregate particles of fuel of predetermined fineness from the more coarse particles thereof, means operable to deliver the more coarse particles of fuel to the other end of the fire box from said fire arch, and means operable to deliver the finer particles of fuel into the fire box adjacent the other end thereof at a point affording a maximum distance of travel for said fine particles of fuel through said fire box.
5. A steam locomotive having a fire box and a fire arch extending inwardly of said fire box from one end wall thereof, a fuel hopper, a trough including upper and lower chambers disposed be-

low said hopper and arranged to receive fuel therefrom, means for separating said chambers adjustably operable and constructed to permit fuel of predetermined fineness to pass to the lower chamber, means mounted in the upper chamber operable to deliver the more coarse particles of fuel therein to the other end of the fire box from said fire arch, and means in the lower chamber operable to deliver the finer particles of fuel therein into the fire box adjacent the other end thereof at a point affording a maximum distance of travel for said fine particles of fuel through said fire box, said delivery being below and in a direction opposite to the delivery of the more coarse particles of fuel.
